UNITED STATES PATENT OFFICE.

PHILIPPE DE CLAMECY, OF BOSTON, MASSACHUSETTS, ASSIGNOR TO CORONA TYPE-WRITER COMPANY, INC., A CORPORATION OF NEW YORK.

TYPE-WRITING MACHINE.

1,278,878.

Specification of Letters Patent. Patented Sept. 17, 1918.

Application filed March 6, 1916. Serial No. 82,407.

To all whom it may concern:

Be it known that I, PHILIPPE DE CLAMECY, a citizen of the United States, and a resident of Boston, county of Suffolk, and State 5 of Massachusetts, have invented certain new and useful Improvements in Type-Writing Machines, of which the following is a full, clear, and exact description.

This invention relates more particularly 10 to the ribbon mechanism of foldable front-strike or other visible typewriting machines.

One of the principal objects of the invention is to provide a typewriting machine 15 in which the platen carriage and its support may be folded rearwardly and downwardly within the main frame of the machine and a part of the ribbon mechanism adapted also to fold to a compact position 20 but independently of the folding movement of the platen carriage in order that those parts normally above the frame of the machine may be moved from such position to a more compact one thus adapting the machine 25 for transportation and other purposes.

A further object of the invention is to provide simple and efficient ribbon mechanism and operating means therefor which is adapted to move the ribbon lengthwise in 30 either direction and which permits part of the ribbon to be moved with its holding means to a compact position independent of the lengthwise feed mechanism.

A still further object of the invention is to 35 provide simple and efficient means whereby ribbon spools may be frictionally held against too free movement.

With these and other objects in view, the invention will be hereinafter more particularly described with reference to the accompanying drawings, which form a part of this application, and will then be pointed out in the claims at the end of the description.

45 In the drawings, Figure 1 is a longitudinal section, partly in elevation, of one form of the machine embodying the invention.

Fig. 2 is a front elevation,

50 Fig. 3 is a partial plan view.

Fig. 4 is a fragmentary view, partly broken away, of a part of the universal bar

and part of the mechanism operated thereby for moving the ribbon spools.

Fig. 5 is an enlarged fragmentary view 55 of the knee or knuckle joint of the two-part key-operated levers to adapt one part to fold relatively to the other; and

Fig. 6 is an enlarged section, partly in elevation, of the retaining pin for holding 60 the platen carriage against folding movement.

The main frame or main frame part 10 has upright corner pillars or posts 11 with the usual rubber tips or feet 12 and connecting the posts at the lower portion thereof is a base 13. At the upper portion of the main frame part is a top plate or member 14 and there may be side plates if desired, it being understood that the frame, or main 70 frame part, may be of the usual or of any preferred construction. At the forward portion of the machine is a keyboard frame part 15. This keyboard frame part 15 is hinged at 16 to the main frame part and at 75 the outer portion thereof may be provided with rubber feet of the usual kind. The keyboard frame part is tray-like in form and is adapted to fold upwardly and inwardly as shown in dotted lines in Fig. 1. The 80 hinge or pivot 16 is in the form of bolts located on opposite sides of the main frame part in alignment, and said bolts have threaded stems which are engaged by thumb nuts 17 which assist in holding the keyboard 85 frame part in its folded and in its normal operative position. This keyboard frame part 15 at its inner portion is provided with an abutting surface 18 which is adapted to engage a substantially L-shaped spring 19 90 secured to the frame base 13 so as to position and hold said frame part in a normally horizontal position, and in the folded position of said frame part the latter is retained in such position by means of a spring 95 20, one end of which is secured to the under surface of the frame part 13 or otherwise held as desired, the thumb nuts 17 serving as additional holding means for said frame part.

A keyboard 21 is mounted to move with the keyboard frame part 15. This keyboard may be of a universal or standard kind and comprises keys 22 which are ar-

ranged in banks or groups and are mounted upon the upper ends of vertical portions of levers 23. The levers 23 are each formed in two parts 24 and 25. The parts 24 and 25⁵ are in alinement when in a normal operative position and all of the parts of said levers are pivotally held to a transversely extending rod 26. The rod 26 is held in the main frame part of the machine between the forward corner posts 11 of the main frame part or in any other desired way. The parts 25 of the key-operated levers extend horizontally and are in alinement with the horizontal portions of the parts 24, and on one 10 of said parts, as the part 24 of each lever, is a shoulder 27 which is adapted to engage a shoulder 28 of the part 25 when in a normal operative position as shown in Fig. 1, so that on the depression of one of the keys 22 the inner end of the part 25 of the two-part lever on which the key is mounted will be forced upwardly. Each lever 23 is restored from a depressed position to its normal operative position by a spring 29, one 15 end of which is secured to the base 13 and the other end passed through an aperture in the key lever part 25. The shoulders 27 and 28 and the mountings of the parts 24 and 25 provide a knee or knuckle joint which 20 adapt all of the parts 24 of all of the key-operated levers to fold relatively to the parts 25 as shown in dotted lines in Fig. 1.

The inner ends of the parts 25 of the key-operated levers 23 have a pin 30 and each pin is adapted to move in a slot 31 of an arm 32. The arm 32 forms a part of the bell-crank lever 33 and each bell-crank lever is pivotally held in a bracket 34 extending upwardly from the base 13 or to a common 25 pivot rod, preferred. The arm 35 of each bell-crank lever 33 is pivotally held by a knee or other joint at its outer end 36 to an upwardly extending link 37, and said link 37 at its upper end is pivoted at 39 to the short arm 40 of a type-bar 41. Each type-bar 41 is adapted to have a plurality of type or characters thereon according to whether a single case shift or double case shift is employed. The type-bars are adapted to 30 rest at their forward ends upon a felt, rubber or other cushion 42 and are arranged in a curved path within the type basket 43, said type basket being suitably held in the main frame part of the machine in such a 35 way that when a key-operated lever is moved on the depression of a key, the actuation of its coöperating bell-crank lever 33 will force a link 37 downwardly and this will cause one of the type-bars to move the type upwardly 40 and rearwardly to make an impression upon the work sheet about the platen 44 in the usual way.

As a means to lock the keys and the foldable parts of the key-operated levers to fold

and unfold together, a bar 45 extends transversely of the machine over the parts 24 and under the parts 24 is a substantially U-shaped rod 46. The rod 46 is pivotally mounted between the sides of the shallow frame part 15 and is adapted to be forced to the position shown in dotted lines in Fig. 1 so that the transversely extending portion 47 will lie directly under the parts 24 of the key-operated levers thus holding the parts 24 of said levers which fold between 75 the transversely extending bar 45 and the portion 47 and thereby prevent their disarrangement. The bar 45 may have a rubber or other strip forming an engaging surface for the key-operated levers, and the rod 46 80 may have a knob or handle to move the same, it being understood that the key-lever parts 24 are not held so tight between the bars 46 and 47 as will prevent such relative movement of the keyboard frame part 15 85 and the key-lever parts 24 as is necessary because of their different pivot points. If desired the pivots of the levers and the keyboard frame part may have a common axis or pivot rod or shaft. 90

The platen 44 is mounted upon a platen carriage 48. This platen carriage 48 is adapted to travel transversely of the machine on a foldable support 49. This support 49 has two members 50 and 51 which 95 are hinged together at 52 at the upper portion of the machine. The support member 50 rests when in a normal operative position upon a transversely extending bar 53 forming a part of the vertically movable 100 member 50 of the platen carriage support. The platen carriage may be variously constructed. As shown it comprises end pieces or brackets 54 which extend upwardly from a carriage base 55 and said base may be held 105 to travel transversely of a carriage bed. The carriage bed may extend rearward as far as the hinge 52 or may be supported between foldable arms or in any other desired way. The carriage end pieces 54 support the axis 110 or shaft 56 of the platen and said end pieces may also support a paper apron 57 in which may be mounted a pressure or feed-roll 58, there being paper fingers and such other parts as are usually employed to hold and 115 guide the work about the platen.

While the platen carriage with its bed forming one member of the carriage support is adapted to fold rearwardly and downwardly so as to extend within the main 120 frame part 11 and between the sides thereof when in a compact position as shown in dotted lines in Fig. 1, the platen carriage and both members of the support are adapted to be shifted for upper case characters 125 when in a normal operative position; though it will be understood that the platen carriage may have two shift movements in-

stead of one, or the type basket itself may be shifted as in some forms of writing machines, if desired. The particular form of case shift mechanism is not described in detail as such mechanism may be of any suitable construction.

The platen carriage and its support may be held in its normal operative position against relative backward folding movement in any desired way. As shown, a pin or stem 59, Fig. 6, has a knob or head 60 thereon and is normally forced inward by a spring 61. The pin 59 is adapted to engage an aperture 62 in one end of the carriage bed or other part and lock said bed to the vertically moving supporting member 50 so that the platen carriage cannot fold rearwardly until the pin is released. The platen carriage may also be held against a swinging or free movement when in its folded compact position by a releasable pin or part 63 or otherwise, which is held to the frame of the machine and is adapted to engage under a part of the foldable carriage supporting member 51 when in its compact position, as shown in Fig. 1.

The ribbon holder 64, is located substantially centrally of the machine and is adapted to support a ribbon in position to cover the printing point on the platen 44. The ribbon holder 64 is pivoted at 65 to a part of the main frame and on opposite sides of the holder, adjacent to its pivot 65, are springs 66 and 67. The spring 66 is secured to the foldable part of the carriage supporting member 51 to fold therewith while the spring 67 is held to a fixed part. The spring 66 is of greater strength than the spring 67 so that when the spring 66 is in the position shown in Fig. 1 the holder will be held against downward folding movement, but when the spring 66 is folded away from the holder 64 to the position shown in dotted lines in said figure the spring 67 will force the holder rearwardly and downwardly on its pivot to a compact position. That is, the ribbon holder will fold over to a substantially horizontal position, carrying the ribbon held thereby and may be restored to its normal operative position manually or otherwise when the platen carriage is restored to its normal operative position. The ribbon from the holder 64 passes about ribbon spools 68 and 69 mounted upon downwardly extending arms 70. The ribbon spools may be detachably held to permit the ribbons to be readily replaced and said ribbon spools may each be frictionally held to its support against too free movement by a spring 71 which may be in the form of a strip or as a disk as preferred. The ribbon spools may have a toothed disk portion or ratchet wheel 72 as a part thereof and adapted to engage the teeth of the ratchet wheels are pawls 73.

The pawls 73 are mounted upon arms 74, 85 held to the vertical rods 75 so that during the reciprocation of the rods 75 the pawls 73 will impart a rotary step-by-step movement to the ribbon spools to wind the ribbon from one spool on to another. The rods 75 are 70 formed as extensions of a universal bar 76 and move therewith. This bar 76 extends transversely of the machine over the key-operated levers and has upwardly extending ends or parts 77 which are guided in tubular 75 posts or guides 78. The universal bar is normally forced downwardly in the path of the key-operated levers by springs 79, and when said bar is operated by the key-operated levers the ribbon spools will be rotated as already described. The pawls 73 and the direction of the teeth of the ratchet disks 72 may be reversed to permit the spools to be rotated during the downward movement of the universal bar instead of the upward movement thereof.

While the drawing shows both pawls 73, in engagement with the teeth of the ratchet wheels of the ribbon spools only one pawl is in engagement at a time, and these pawls 90 may be moved to engagement or disengagement manually and independently or they may be moved simultaneously as is common in some forms of typewriting machines, whereby one pawl is disengaged when the other pawl is engaged in order that the direction of feed of the ribbon may be reversed at will.

The escapement mechanism has not been described herein and so far as the present invention is concerned such mechanism may be of any suitable construction. The escapement mechanism, key action, platen shift and certain other features shown are not claimed herein as they form part of separate applications filed by me.

Having thus described my invention, what I claim as new and desire to secure by Letters Patent, is:—

1. In a typewriting machine, the combination of a frame, key-operated levers pivotally supported in the frame intermediate their ends, a universal bar extending transversely above the rear ends of the key-operated levers and adapted to be engaged and elevated thereby, upwardly extending posts held to the universal bar at their lower ends, tubular guides for said posts held to the frame, ribbon spools, horizontally extending shafts for said spools held to the frame, 110 ratchet wheels held to the spools, arms held to the universal bar to move up and down therewith, and pawls carried by said arms adapted to engage and rotate the ratchet wheels when the universal bar is reciprocated by the key-operated levers.

2. In a typewriting machine, the combination of a frame, key-operated levers pivot-

ally supported in the frame intermediate their ends, a universal bar extending transversely above the rear ends of the key-operated levers and adapted to be engaged and elevated thereby, upwardly extending posts held to the universal bar at their lower ends, tubular guides for said posts held to the frame, ribbon spools, horizontally extending shafts for said spools held to the frame, ratchet wheels held to the spools, arms held to the universal bar to move up and down therewith, pawls carried by said arms adapted to engage and rotate the ratchet wheels when the universal bar is reciprocated by the key-operated levers, and resilient means for normally forcing the universal bar downwardly.

3. In a typewriting machine, the combination of a frame, key-operated levers pivotally supported in the frame intermediate their ends, a universal bar extending transversely of the frame above the rear ends of said levers and adapted to be engaged and elevated thereby, upwardly extending posts held to the universal bar at their lower ends, tubular guides for said posts held to the frame, ribbon spools, horizontally extending shafts for said spools held to the frame, ratchet wheels held to the spools, arms held to the universal bar to move up and down therewith, pawls carried by said arms for rotating the ratchet wheels, and springs coiled about said upwardly extending posts and interposed between the universal bar and said tubular guides for returning the universal bar to its normal position.

4. In a typewriting machine, the combination of a frame, ribbon spools, horizontally extending shafts for said spools held to the frame, ratchet wheels held to said spools, a substantially U-shaped universal bar having a portion extending transversely of the machine and vertically extending end members, means held to the frame and engaging the end members of the universal bar for slidably guiding said bar vertically, arms held to the universal bar to reciprocate vertically therewith, and pawls carried by said arms for rotating the ratchet wheels.

5. In a typewriting machine, the combination of a frame, ribbon spools, horizontally extending shafts for said spools held to the frame, ratchet wheels held to said spools, a substantially U-shaped universal bar having a portion extending transversely of the machine and vertically extending end members, means held to the frame and engaging the end members of the universal bar for slidably guiding said bar vertically, arms held to the universal bar to reciprocate vertically therewith, pawls carried by said arms for rotating the ratchet wheels, and key-operated levers pivotally held to the frame intermediate their ends, the rear ends of said

levers extending under the transversely extending portion of the universal bar and being adapted to engage and elevate the bar when the keys are depressed.

6. In a typewriting machine, the combination of a frame, ribbon spools, horizontally extending shafts for said spools held to the frame, ratchet wheels held to said spools, a substantially U-shaped universal bar having a portion extending transversely of the machine and vertically extending end members, means held to the frame and engaging the end members of the universal bar for slidably guiding said bar vertically, arms held to the universal bar to reciprocate vertically therewith, pawls carried by said arms for rotating the ratchet wheels, and springs interposed between said guiding means and the transversely extending portion of the universal bar for normally forcing the universal bar downwardly.

7. In a typewriting machine, the combination of a frame, ribbon spools, horizontally extending shafts for said spools held to the frame, ratchet wheels held to said spools, a substantially U-shaped universal bar having a portion extending transversely of the machine and vertically extending end members, means held to the frame and engaging the end members of the universal bar for slidably guiding said bar vertically, arms held to the universal bar to reciprocate vertically therewith, pawls carried by said arms for rotating the ratchet wheels, key-operated levers pivotally held to the frame intermediate their ends, the rear ends of said levers extending under the transversely extending portion of the universal bar and being adapted to engage and elevate the bar when the keys are depressed, and springs interposed between said guiding means and the transversely extending portion of the universal bar for normally forcing the universal bar downwardly toward the rear ends of the key levers.

8. In a typewriting machine, the combination of a frame, key-operated levers pivotally supported in the frame intermediate their ends, a universal bar extending transversely above the rear ends of the key-operated levers and adapted to be engaged and elevated thereby, upwardly extending posts held to the universal bar at their lower ends, tubular guides for said posts held to the frame, ribbon spools, horizontally extending shafts for said spools held to the frame, ratchet wheels held to the spools, arms held to the universal bar to move up and down therewith, pawls carried by said arms adapted to engage and rotate the ratchet wheels when the universal bar is reciprocated by the key-operated levers, and springs frictionally engaging ends of the spools.

9. In a typewriting machine, the combina-

tion of a frame, ribbon spools, horizontally extending shafts for said spools held to the frame, ratchet wheels held to said spools, a substantially U-shaped universal bar having 5 a portion extending transversely of the machine and vertically extending end members, means held to the frame and engaging the end members of the universal bar for slidably guiding said bar vertically, arms held to the universal bar to reciprocate vertically 10 therewith, pawls carried by said arms for rotating the ratchet wheels, and springs having their free ends frictionally engaging the ends of said spools.

This specification signed this 2d day of 15 March, A. D. 1916.

PHILIPPE DE CLAMECY.
